UNITED STATES PATENT OFFICE.

LORENZO R. GAGE, SR., OF HOQUIAM, WASHINGTON.

GOLD-DREDGE.

1,270,142.

Specification of Letters Patent. Patented June 18, 1918.

Application filed April 27, 1917. Serial No. 165,021.

To all whom it may concern:

Be it known that I, LORENZO R. GAGE, Sr., a citizen of the United States, residing at Hoquiam, in the county of Grays Harbor 5 and State of Washington, have invented certain new and useful Improvements in Gold-Dredges; and I do declare the following to be a full, clear, and exact description of the invention, such as will enable others 10 skilled in the art to which it appertains to make and use the same.

My invention relates to dredges and more particularly to suction dredges which are operated to obtain gold, platinum, or other 15 valuable metals from the beds of streams or rivers.

The principal object of my invention is to provide in a dredge of this character a novel form of suction head in which means are 20 provided to force the material away from the front of the head so as to permit easy passage of the head through the ore-bearing material.

Another object of my invention is to provide 25 on the suction head means whereby obstructions and large lumps of material which cannot be passed through the head itself may be readily removed and passed over and away from the head without obstructing the 30 passage of the same.

Another object of my invention is to provide in a suction head on a dredge of this character means to control the flow of ore-bearing material through the head, and 35 means to regulate the velocity of the material passing through the same.

A further object of my invention is to provide in a dredge of this character means whereby disintegrating jets are directed 40 against the ore-bearing material in front of the head in such a manner that they will co-operate with mechanism carried on the head itself, whereby to disintegrate the material in front of the head to permit ready passage 45 of the ore-bearing material through the head itself.

A still further object of my invention is to provide a dredge of this character which embodies a novel construction and arrangement 50 of parts and which is easily operated and adaptable to all conditions under which it might be called upon to operate.

With these and other general objects in view which will appear from the description, 55 my invention resides in the novel construction, combination, and arrangement of parts

to be hereinafter more fully described and claimed and taken in connection with the accompanying drawings which form a part of this application, and in which:

60

Figure 1 is a side elevation of a dredge embodying my invention;

Fig. 2 is a vertical transverse section on the line 2—2 of Fig. 1;

Fig. 3 is a longitudinal vertical section 65 taken through my improved suction head;

Fig. 4 is a top plan view of the head, the conveyer being shown as removed;

Fig. 5 is a transverse vertical section 70 through the head taken on the line 5—5 of Fig. 3; and

Fig. 6 is a horizontal section on the line 6—6 of Fig. 3.

Briefly described, my invention comprises substantially a portable body provided with 75 suitable propelling means and having a sluice box mounted on the upper portion of the body frame. Depending from the frame and supported by means of a pipe having communication therewith is disposed a suction head for gathering ore-bearing material from the bottom of streams, rivers, and the like. Means are provided for raising and lowering the head with respect to the body frame, and a suitable pump is mounted 85 on the frame for drawing material through the head and through the supporting pipe, and is disposed for discharge into the upper end of the sluice box mounted on the body frame.

90

Means are provided for directing water against the material in front of the suction head whereby the head will be allowed to travel easily over the ore-bearing material, which means comprises a force pump suitably mounted on the body frame and having connection with a series of nozzles disposed suitably with respect to the suction head to accomplish the desired result. As a means of removing obstructions from the path of 100 the head, a conveyer is mounted on the head itself and an operating connection extends between a suitable motor mounted on the frame and the conveyer for actuating the same, whereby all obstructions and pieces of 105 material too large to be entered in the intake of the suction head will be picked up and conveyed away from the mouth to the intake, thereby preventing clogging of the same.

Referring more particularly to the drawings in detail, I have shown and described in this embodiment, my invention as ap-

plied to a dredge comprising a frame 1 constructed of heavy steel beams or other suitable material and mounted upon suitable tractor wheels 2. The two rear wheels are 5 provided with suitable tractor members and are connected by means of a belt drive or sprocket and chain gearing connection to a motor 3 which is suitably disposed at any desired point in the body frame 1 for driving connection for the dredge frame. Suitable gearing is provided for throwing the motor drive in or out of engagement as desired, and a means for propelling the frame 10 forwardly is provided at the front end of the same and consists of a capstan or windlass 4 suitably adapted for operation and upon which is wound a cable 5 having its free end adapted for connection to any suitable anchorage disposed at a desired point 15 on the banks of the stream or at any place preferred in advance of the machine for drawing the same thereto.

This means of transportation and drive as well as the manner of mounting the frame 20 is merely described and illustrated in order to show one manner of applying my invention, and I desire it to be understood that I do not limit myself to this specific form as it is obvious that the invention may be 25 used upon any suitable frame mounted in any desired manner, depending entirely upon existing individual conditions, which may call for the use of floats instead of tractor wheels, or for sled runner supports, 30 or in fact, for any type of support or means of propelling the machine, the construction and type used being controlled entirely as I have stated above, by the exigencies of 35 the individual conditions under which the 40 machine will be called upon to operate.

Suitably mounted on the body frame of the dredge and inclined downwardly from its front to its rear end, is disposed one or 45 more sluice boxes 6 as may be desired, into the upper end of which is adapted to discharge the suction pipe which is connected to the suction head as will be hereinafter described. At the rear end the sluice box is provided with an outlet chute for dis- 50 charging the tailings at the rear of the machine. Depending from the body of the dredge frame is a suction head 7, the details of which will be hereinafter described, which is provided with the conveyer pipe 55 extending from its rear end as at 8 and connected to a communicating conveyer pipe rigidly mounted in the body of the dredge frame as at 9, which pipe discharges into the upper elevated front end of the sluice 60 box 6. Connected to the pipe 9 and disposed at any suitable point on the dredge frame is a powerful suction pump 10 operated from the motor 3 by means of suitable gearing or by any other source as desired, 65 for drawing the ore-bearing material up

through the suction head, and communicating pipes to discharge the same into the sluice box. At the rear end of the machine the conveyer pipe 9 is extended downwardly and secured by means of a bracket 11 and 70 is hingedly connected at its lower end to the conveyer pipe 8 leading from the suction head, whereby to permit of a vertical swing of the head in order that the same may be drawn up against the bottom of the 75 dredge frame when it is desired to suspend operation of the dredge. The downwardly projecting portion of the pipe 9 with the hinged connection carrying the conveyer pipe 8 is so disposed that when the suction 80 head 7 is in lowered position, the line of strain, owing to the forward movement of the dredge, will be taken up by the pipe 8 and on the hinged connection with the pipe 9 at the point of connection as at 12, whereby an efficient brace will be provided which will evenly distribute the strain, thereby 85 eliminating all danger of any undue stress being placed upon parts of the dredge which are not calculated to withstand the strain 90 applied. The connection just described forms one element of a support for the suction head, the other element of the support comprising a stirrup 13 composed of a pair of substantially triangular metal 95 arms riveted to the sides of the head 7 and apertured at their upper ends to receive the free end of a cable or chain connected to a windlass 14 suitably disposed at any desired point on the frame of the dredge, 100 whereby the suction head 7 may be raised or lowered as desired on the hinged connection 12.

Having thus described in detail the connection of the conveyer pipes leading from the suction head to the sluice box, with the suction pump in connection therewith, as well as the means for vertical adjustment of the suction head, I will now pass to the description of the head itself and its 105 improved and novel manner of construction, in detail. The head comprises a substantially wedge-shaped body having its top and bottom converging from its rear to its front end, and its side walls diverging from 110 its rear to its front end, and being substantially rectangular in cross section.

To the side walls 15 of the head are riveted or otherwise suitably secured, the arms 13 as hereinbefore described, and connected through the rear wall 16 of the suction head is disposed the suction conveyer pipe 8 leading to the sluice box on the body of the dredge as described. A removable top 17 is provided for the head which extends from the rear wall 16 to a point spaced inwardly and adjacent the front end and is secured to the walls of the head by means of suitable clamping members actuated by handles 18 by which the top may 115 120 125 130

be removed when it is desired to reach the interior of the chamber formed within the suction head for the purpose of cleaning or adjusting the same. Inclined downwardly from the top toward the bottom and slanted toward the front end of the head and disposed adjacent said end but spaced inwardly therefrom, is a flat bar or plate 19 which is formed integrally with the side 5 walls 15 of the head and extends transversely therebetween. The lower edge of this plate is spaced above the bottom of the head to provide an intake slot adjacent the front end of the head designated at 20. 10 Owing to the disposition and inwardly spaced arrangement of this plate 19, the intake slot will be spaced inwardly from the end of the head, which end will form an outwardly projecting shovel lip 21 comprising 15 the outer end portions of the two side walls and the bottom of the head. This shovel lip portion 21 will project outwardly beyond and below the bottom slot 20 and will enter the material to be dredged and 20 receive and guide the same thereon inwardly through the intake slot to the chamber within the suction head, from whence it is suitably conveyed to the sluice box 25 on the frame of the dredge as hereinbefore 25 described.

I provide a closure plate 22 which is adapted to slide over the plate 19 and project downwardly over the lower edge thereof to regulate the size of the intake slot 20. 30 The two plates 19 and 22 respectively are provided with aligned elongated apertures in their central portions through which is extended a bolt or other suitable fastening member 23 by which the plate 22 may be adjusted at any desired point on the plate 19 to regulate the size of the intake aperture 40 20. This plate 22 is formed to conform in outline with the inclosing walls 15 of the head so that it will readily move within the 45 same without binding upon the side walls.

Spaced slightly inwardly from the intake slot 20 and disposed within the chamber formed at the interior of the suction head is mounted a swinging foot valve 24 journaled 50 between the side walls for oscillation therebetween and connected to any suitable operating means disposed externally of the walls of the suction head which may or may not be connected to the operating mechanism 55 disposed on the frame of the dredge, as desired. The function of this valve which swings inwardly, upon being actuated, is to regulate the pressure of the flow of the material therethrough. It coacts with the regulating plate 22 disposed over the intake slot 20 to regulate the size and velocity of the material passing through the suction head. Disposed entirely over the base or bottom of the suction head and suitably secured at its 60 65 front end to the bottom of the head in such

a manner that the rear end is allowed to swing vertically in the chamber formed in the head, is a riffle plate 25 which is provided at spaced intervals with a series of transversely arranged parallel riffle members 26 for a purpose to be hereinafter described. The front end or edge of this baffle plate is secured substantially at the base of the foot valve 24, and is apertured adjacent its rear end to receive therethrough the stem 70 of a bolt 27 extending upwardly from the bottom of the suction head and suitably mounted therein with a portion thereof extending externally of the bottom and provided with means whereby the stem may be 75 rotated to raise or lower the adjacent end of the baffle plate 25 within the chamber.

The connection between the riffle plate and the bolt stem may be any specific construction desired and I do not confine myself to any particular details of this connection other than to generally show a nut member 28 which is so connected to the riffle plate and threaded on the bolt stem that it may be moved upwardly and downwardly upon 80 the stem when the same is actuated to raise or lower the baffle plate within the chamber. The angle at which the baffle plate is secured is an important factor in determining and adjusting the velocity at which the material 85 being dredged is permitted to flow through the suction head, and comprises an important part of my invention, inasmuch as it forms an ore separating means within the suction head, rendering the suction head 90 practically a sluice box in itself.

As the ore carrying material is discharged inwardly through the intake slot and foot valve aperture against the angled riffle plate 25, the particles of the material will be 105 broken up upon impact with said plate, and the heavier ores and precious metals will be caused to settle in the pockets formed by the riffle members 26, whereby they may be collected and retained within the suction 110 chamber, thereby preventing the loss of valuable metals which would otherwise be dislodged from the mass of ore-bearing material and settle back out of the intake slot and be lost along the bed of the stream or 115 river in which the machine is operating. The suction pipe 8 preferably enters the chamber formed within the suction head through the rear wall and centrally disposed in the wall and is spaced above the bottom 120 of the suction head and adjacent the top so as to insure of the separating chamber with the riffle plate and riffles therein operating at all times under full capacity.

In the forward motion of the machine, 125 considerable pressure is required to force the shovel lip 21 inwardly into the material being dredged at the front of the suction head, and as a means of reducing this pressure and thereby providing a more efficient 130

dredge, I provide a chamber 29 formed on the bottom of the suction head adjacent the shovel lip and consisting of the outwardly flared walls 30 and the bottom portion 31 which are provided at the inner end with a connection to the pressure pipe 32 to be hereinafter described, and which are so arranged with respect to the front edge of the shovel lip 21 that the bottom portion or wall 31 of the chamber 29 will be disposed slightly below the bottom portion of the shovel lip and have its outer end spaced below and in parallel relation with the edge of the lip 21, whereby to provide a nozzle 10 for the discharge of a transversely disposed hydraulic jet in advance of the shovel lip 21 which will tend to disintegrate the material in front of the lip and considerably reduce the pressure required to force the lip 20 through the material.

The nozzle chamber 29 is formed preferably over only a portion of the base of the suction head adjacent the front edge and is in connection with the pressure pipe 32 which 25 is extended rearwardly along the bottom of the suction head and secured by suitable brackets or retaining members and is in communication by means of a flexible connection 33 with the discharge pipe 34 of a 30 force pump 35 which is disposed at any desired advantageous point on the body of the dredge frame and which is provided with an intake 36 normally extending downwardly into the stream or river in which the 35 dredge is operating so that the pump will be supplied with water in order to produce a hydraulic jet of considerable force below the mouth of the shovel lip 21 as described.

Depending from the frame of the dredge 40 and connected to the discharge pipe 34 of the force pump, is a spur pipe 37 extending downwardly and spaced in advance of the suction head and which is provided at its lower end with a nozzle portion 38 having 45 hinged connection as at 39 with the spur pipe 37 so that the nozzle portion 38 will be disposed on the top of the material comprising the bed of the stream in such a manner that it may be drawn thereover when the 50 dredge is carried forward and allowed, owing to the hinged connection 39, a certain flexibility when brought into contact with boulders or other objects disposed on the bed of the stream and in the path of the 55 member. The nozzle portion 38 of the spur pipe 37 is directed rearwardly of the machine and disposed for discharge slightly above and in advance of the suction head, and its function is to deliver at all times a 60 disintegrating jet at the surface of the ore carrying material in front of the suction head, coacting with the jet from the nozzle disposed below the shovel lip 21 to loosen and dislodge the material in front of the 65 suction head.

It has been found that in the operation of this type of dredge large boulders and other objects will frequently lodge in the mouth of the intake and obstruct the passage of the ore-bearing material through the suction 70 head and in other ways impair the efficiency of the dredge and cause much damage to the parts of the suction head with which they come in contact. To eliminate all possibility of conditions such as I have described arising, I provide a means to act as a guard for the mouth of the intake slot 20 which is so adapted to act as a conveyer to break up the material adjacent the intake and convey the boulders and unbreakable parts of the material 80 away from the intake and deposit the same at the rear of the suction head so that they will not interfere with the future operation of the head. The means which I have described comprises a series of sprocket 85 wheels 40 mounted on a shaft 41 secured in the two side walls of the suction head and at the front end of the head and disposed in advance of the inclined cover plate 22.

Suitably secured to the sides 15 of the 90 suction head and at the rear end thereof are brackets 42 adapted at their outer ends to receive therethrough a shaft 43 on which is mounted a plurality of sprocket wheels 44 in longitudinal alinement with the sprocket 95 wheels 40 on the shaft at the front end of the suction head. At one end of the shaft 43 a worm wheel 45 is splined thereon for operative engagement with a worm 46 increased in a suitable protective casing 47 and 100 suitably secured by brackets or any suitable means to the suction head. The worm 46 is operated through the medium of a flexible connecting gearing 48 extending to and having connection with the motor on the dredge 105 frame or having connection with any suitable source of power desired.

Extending over the sprocket wheels are 110 endless chains 49 and transversely extending between these chains and suitably connected thereto are spaced bars 50 having up-raised fingers or teeth 51 formed thereon at spaced intervals to form an endless conveyer 115 on the top of the suction head, so that when the worm 46 is actuated through the medium of the gearing connected to the motor on the frame of the dredge, the conveyer will be actuated, and owing to the disposition of the forward sprocket wheels 40 of the conveyer, large lumps of material will 120 be collected from the front of the suction head and carried upwardly away from the head and dropped at the rear of the suction head. The fingers 51 formed on the conveyer will also act as a series of rake teeth 125 and form guard bars disposed in front of the intake slot 20 to prevent large pieces of material from clogging therein. The conveyer is suitably elevated above the top of the suction head by means of rollers 52 130

mounted in standards 53 extending upwardly from each side of the suction head at the point of commencement of the downward incline of the plate 19.

- 5 Owing to the wedge-shaped construction of the head and the inclined disposition of the intake slot adjusting plate 22, it will be seen that independently of the conveyer mounted on the top of the head, the material 10 will be caused to travel upwardly over the head when the particles are too large to be passed through the intake slot. By the addition of the conveyer, and owing to its disposition at the front end by which it acts as 15 a guard for the intake slot, positive means are provided for disintegrating the material in front of the suction head and conveying away the larger particles and depositing them at the rear of the head as described. 20 The conveyer is greatly assisted in its operation by means of the rearwardly directed hydraulic jet emanating from the nozzle portion 38 of the spur pipe 37 in connection with the force pump 35 on the frame of the 25 dredge.

Hence it will be seen that I have provided a dredge which is very efficient in operation and is designed specifically to meet the requirements of the varying conditions encountered in the operation of dredges of this character in the most efficient manner possible. Owing to the vertical adjustment permitted by the construction of the suction head, it will be seen that my dredge is enabled to cover a wide range in its operation, and owing to the coaction of the hydraulic jets and the conveyer disposed at the top of the suction head, any lodging of the material in the mouth of the intake or any 40 blocking of the forward travel of the head by large obstacles in the path of the same is

effectively prevented by this improved and novel construction, combination and arrangement of parts embodied in my invention. I desire it to be understood that I do 45 not limit myself specifically to the details of construction as described herein, but that any changes may be made in the details of construction and the manner of operation of my dredge without departing from the 50 spirit of the invention as may fall within the scope of the appended claims.

I claim:

1. In a precious metal dredge, a suction conduit, and a box-like suction head communicating at its rear end with said conduit, the front end of said head being inclined downwardly and forwardly and having at its lower edge an inlet, the sides and bottom of said head being extended forwardly beyond 55 said inlet to provide a shovel lip.

2. In a precious metal dredge, a suction conduit, a box-like suction head communicating at its rear end with said conduit, the front end of said head being inclined downwardly and forwardly and having at its lower edge an inlet, the sides and bottom of said head being extended forwardly beyond 60 said inlet to provide a shovel lip, conveyer guides adjacent the upper and lower edges 65 of said front end of the head and above the rear end of said head, and a driven conveyer trained around said guides for conveying rock rearwardly over the head to prevent clogging of the inlet thereof. 70

In testimony whereof I have hereunto set my hand in the presence of two subscribing witnesses.
